MASSAGING DEVICE

Leland H. Snyder, Chicago, Ill., assignor, by
mesne assignments, to Knapp-Monarch Com-
pany, St. Louis, Mo., a corporation of Delaware

Application February 17, 1947, Serial No. 729,000

3 Claims. (Cl. 128—41)

1

This invention relates to an electromagnetic vibrator construction, and particularly to a vibrator construction utilized in electromagnetically operated massaging devices.

An object of this invention is to provide an improved vibrator construction characterized by the simplicity of manufacture and assembly of its components and particularly by the fact that all of the major components of the device may be produced by low cost, high quantity production methods such as stamping and molding operations and no machining of any components is required.

Another object of this invention is to provide an improved construction for mounting the armature and magnetic core structure of a vibrator unit within a recessed casing, characterized by the utilization of a single fastener for effecting the clamping of the magnetic laminations and the rigid securing of such laminations to a unitary spring and armature member.

Still another object of this invention is to provide an improved vibrator construction for a hand held massaging device wherein an armature member is resiliently supported with respect to a magnetic core structure and in addition, both the core structure and armature are resiliently supported for vibratory movement with respect to the recessed casing in which they are mounted.

The specific nature of the invention as well as other objects and advantages thereof will become apparent to those skilled in the art from the following detailed description of the annexed sheet of drawings which, by way of preferred example only, illustrate one specific embodiment of the invention.

On the drawings:

Figure 1 is an elevational view of an assembled massaging device incorporating this invention;

Figure 2 is a sectional view taken on the plane II—II of Fig. 1;

Figure 3 is a sectional view taken on the plane III—III of Fig. 2;

Figure 4 is a sectional view of the combined armature and spring member employed in the massaging device of Fig. 1.

As shown on the drawings:

A vibrator construction embodying this invention is illustrated as assembled in a massaging device of the type more particularly described and claimed in my copending application Serial No. 587,179, filed April 7, 1945. Such massaging device comprises a casing 1 having a generally ball-shaped exterior such that it may be conveniently grasped by the hand of the operator and defining a cylindrical recess 1a which opens in one end of the casing. While not limited thereto, the casing 1 may be conveniently manu-

2

factured by molding of plastic or other suitable electrically insulating material.

The vibrator construction embodies a laminated magnetic core structure 10 which is of the conventional E-shape, having a base portion 10a and three pole portions 10b projecting from the base portion 10a. When assembled in the recess 1a of the casing, the pole portions 10b preferably lie generally parallel to the axis of the recess and project toward the open end of the casing.

In accordance with this invention, a unitary armature and spring member 12 is provided comprising a stamping of generally U shape having spaced arm portions 14 and 16. The arm portion 14 is in itself deformed into a smaller generally U-shape configuration 14a so as to snugly surround the base portion 10a of the laminated magnetic core structure and thus function as a clamp tending to secure the laminations in assembly. The arm 16 of the unitary armature and spring member 12 is formed with integral lateral extensions 16a and is arranged to be normally positioned in bridging relationship with respect to the end faces of the pole portions 10b of the magnetic core structure 10, but spaced slightly therefrom. The inherent resilience of the U-shaped armature and spring member 12 will, however, permit the end portions of arm 16 to be drawn into engagement with the end faces of the pole portions 10b when the magnetic core structure is magnetically excited.

The exciting coil 18 is mounted in conventional fashion surrounding the central pole portion 10b of the magnetic core structure 10. The electric wires 20 for energizing the solenoid 18 are tied into a strain relief knot 20a and then inserted through a hole in a depending lug 14b which may be conveniently punched out of the arm portion 14 of the armature and spring member 12. The wires then pass outwardly of the casing 1 through a suitable aperture 1b therein.

The vibrator construction is supported within the casing recess 1a by a pair of bracket members 22. Such bracket members are of generally U-shape configuration and have one arm 22a thereof disposed adjacent diametrically separated points of the wall of casing recess 1a. Such arm portions 22a are provided with threaded holes which are in turn respectively engaged by screws 24 which are mounted in suitable apertures 1c provided in the casing wall. The other arm 22b of the bracket members 22 is split at its ends into a plurality of perpendicularly separated finger portions 22c and 22d. The finger portions 22c lie adjacent and parallel to the side face of the magnetic core structure 10, while the finger portions 22d lie adjacent and parallel to the bottom face of the magnetic core structure 10. A single fastener 26 may then be provided, passing respectively through suitable aligned holes in

bracket fingers 22c, clamp shaped end portions 14a and the base portion 10a of the laminated magnetic structure 10. Fastener 26 may conveniently comprise a rivet and, when secured in place, this single fastener effects the rigid securing of the magnetic laminations, the armature and spring member and the bracket.

An applicator device 28 is suitably secured to the outer face of the arm portion 16 of the armature and spring member 12. As described in detail in my above referred to copending application, such applicator preferably is provided with an arcuate exterior surface 28a which effectively constitutes a continuation of the external contours of the casing 1. Furthermore, the peripheral dimensions of applicator 28 are selected so that the open end of recess 1a is substantially closed by the applicator.

The operation of the vibrator construction embodying this invention is believed to be obvious from the foregoing detailed description of its construction. When the solenoid 18 is energized by a suitable source of alternating current, the armature arm portion 16 of the unitary armature and spring member 12 is drawn into engagement with the end faces of pole portions 10b of the magnetic structure 10 each time that the energizing current approaches its maximum value in any particular half cycle. When the current falls off to zero value at the end of each half cycle, the inherent resilience of the unitary armature and spring member 12 moves the armature arm portion 16 thereof away from the pole end faces. Thus a definite vibratory movement is imparted to the applicator 28.

In some designs, it has been found desirable to so proportion the bracket members 22 so that a slight vibratory movement of the arm portion 22b thereof with respect to the fixed arm portion 22a will occur during the operation of the vibrator. It will be noted that the U-shaped configuration of the bracket 22 will conveniently permit a slight vibratory movement of the arm portion 22b in substantially the same direction as the vibratory movement of the armature portion 16. Since the magnetic core structure 10 is of course subjected to equal and opposite reaction forces as are applied to the armature portion 16, the provision of a slight resilience of the bracket 22 may substantially increase the effective vibrating force delivered by the massage applicator 28.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. In a massaging device, a casing shaped to be grasped by hand, said casing defining a generally cylindrical recess opening at one end of the casing, a laminated magnetic core structure insertable in said recess through said open end, said core structure having a base portion and a plurality of pole portions projecting from said base toward said open end of the casing, an armature member of generally U-shape, one arm of said armature member being shaped to snugly surround said base portion of said magnetic laminations to secure said laminations in assembly, the other arm of said armature member having laterally extended end portions nor-

mally disposed adjacent the ends of said pole portions and spaced therefrom but movable against the inherent resilience of the U-shaped member into a bridging position across said

5 pole ends, a pair of brackets of generally U-shape configuration, said brackets having one arm thereof respectively secured to diametrically opposed portions of the wall of said recess, and another arm respectively disposed adjacent opposite faces of said base portion of the magnetic structure, and a single fastener traversing both of said other bracket arms, said one end of said armature member, and said base portion of the magnetic structure to secure said elements in assembly.

10 2. In a massaging device, a casing defining a recess, a laminated magnetic core structure disposed in said recess and having a base portion and a plurality of pole portions projecting from said base, a combination integral armature and 15 spring member of generally U-shape having a clamping portion thereof disposed in partially surrounding relationship to said base portion of said magnetic laminations to secure said laminations in assembly and an armature portion disposed adjacent the ends of said pole portions and normally spaced therefrom but movable against the inherent resiliency of the armature and spring member into a bridging position against said pole ends, a bracket secured to said casing and having a portion extending into said recess and flexibly movable in substantially the same direction as the vibratory movement of said armature portion of said armature member, and common fastening means for securing said bracket portion, 20 said clamp portion, and said magnetic core structure in rigid assembly.

25 3. In a massaging device, a casing defining a generally cylindrical recess open at one end, a laminated magnetic core structure insertable in said recess through said open end, said core structure having a base portion and a plurality of pole portions projecting from said base portion toward said open end of said casing, an armature member of generally U-shape, one arm of said armature member having a clamp shaped end snugly surrounding said base portion of said magnetic laminations to secure said laminations in assembly, the other arm of said armature member having an end portion normally disposed adjacent the ends of said pole portion and spaced therefrom but movable against the inherent resilience of the U-shaped member into a bridging position across said pole ends, a flexible bracket of U-shaped configuration having a first arm secured to a wall of said recess and a second arm extending within said recess, said second arm being resiliently movable with respect to said first arm in substantially the same direction as the vibratory movement of said other arm of the armature member, and a single fastener traversing said second bracket arm, said clamp shaped end, and said magnetic core structure for securing such elements in rigid assembly.
